UNITED STATES PATENT OFFICE.

CHARLES H. LEINERT, OF CHICAGO, ILLINOIS, ASSIGNOR TO LEINERT VALVE COMPANY, OF CHICAGO, ILLINOIS, A CORPORATION OF ILLINOIS.

SPRING AND METHOD OF PRODUCING THE SAME

Application filed March 13, 1924. Serial No. 698,885.

To all whom it may concern:

Be it known that I, CHARLES H. LEINERT, a citizen of the United States, residing at Chicago, in the county of Cook and State of Illinois, have invented certain new and useful Improvements in Springs and Methods of Producing the Same, of which the following is a specification.

This invention relates to a duplex spring having two components which are formed and assembled in a novel and improved manner; it includes also the method employed in the production of such a spring. It is contemplated that the present spring may have a wide utility and be formed to various sizes and shapes according to the particular requirements of its intended use.

In the production of the present spring I have aimed to combine economy in manufacture with durability in service. In addition to these general advantages, the present spring employs two components which co-operate in providing a desired tension over a prolonged period of hard usage; and, in case of one component breaking down, the other component will continue to operate satisfactorily, thereby eliminating the immediate necessity of a complete replacement which may oftentimes be accomplished only with shutting down of the associated mechanisms with a consequent loss and inconvenience. I, furthermore, contemplate the manufacture of the present spring according to a method which is simple and economical, and which assures the production of a spring having uniform characteristics. It is with objects such as these, and also others which will herein-after appear, that my invention is primarily concerned. It may best be understood from the specification following, taken in conjunction with the accompanying drawing wherein—

Figure 1, which is a view partly in elevation and partly in section, shows the outer spring component formed into a coil around a temporary core, this being the initial step which is taken;

Fig. 2 shows the two spring components in assembled relation as they appear after the second step has been taken;

Fig. 3 is a similar view showing the completed spring removed from the heating device which is used in the performance

of the second step required in its manufacture; and

Figs. 4 and 5 represent two different forms into which the spring may be bent for service.

The two components of my duplex spring are a coil A having windings which surround a longitudinally extending core B, each of these parts being formed preferably of suitable spring wire. The coils or windings are fitted tightly upon the core, and in the accomplishment of this end the following procedure is suggested:

The outer wire B is initially formed in coils or windings about a temporary or forming core C (see Fig. 1), and thereafter removed from the core. A length of the spring wire so formed into coils is then placed in suitable supports 6 in proximity to a heater here shown as a gas pipe 7 having burner openings 8. By the operation of an appropriate shut off valve 9, the flame at the burner openings may be regulated. This second step in the spring manufacture will produce an expansion of the coils or windings sufficient for the insertion of the permanent core wire B in place of the forming core C. This core wire B which remains permanently in the spring assembly is of slightly larger diameter than the forming core—perhaps one or two gauge sizes larger. It is receivable centrally through the windings of the outer coiled wire A when the same is in expanded condition under the influence of heat. With the assembly of the core wire B within the windings of the outer wire A, the duplex spring is allowed to cool down, whereupon the windings of the outer wire contract tightly upon the core so as to remain assembled therewith permanently and, for all practical purposes, inseparably. An assembly of the two wires in this manner, however, will not result in any such binding as to interfere appreciably with the spring action of either wire, inasmuch as the coils of the outer wire may separate from each other for the negligible distance required whenever the spring is bent in any direction.

In the production of a duplex spring, according to this invention, it is contemplated that the same will be made to any lengths which are convenient for handling—perhaps

four or five feet. After the outer windings are shrunk upon the permanent core in the manner explained, the spring may be cut to any desired lengths and shapes. It is, of course, retempered to take on the required tension.

As already indicated, a duplex spring of the kind described may be formed to various sizes and shapes according to the use 10 contemplated. A spiral spring form may be adopted such as is shown in Fig. 4, or an M spring, such as appears in Fig. 5, this latter being suitable for use with a compressor valve of the kind set forth in my Patent No. 15 1,240,461, granted September 18, 1917. In such a capacity, it would have special advantage owing to the marked tendency of springs to break from time to time on account of the great frequency of reciprocations which they are called upon to oppose. 20 In such an environment, the present spring would be less likely to break because of its duplex character, the outer windings affording reinforcement to the inner core, so that 25 even if one of these components becomes inoperative, the other would continue to function for an indefinite period.

I claim:

1. A duplex spring having a core of 30 spring wire surrounded by windings of another spring wire which tightly engages the first, as and for the purpose specified.
2. A duplex spring comprising a longitudinal spring wire and a second spring wire 35 coiled into windings therearound and engaged therewith in a manner which connects the one inseparably with the other but without interfering with the spring action of either wire, substantially as described.

3. A spring in which is combined a flexible 40 longitudinal component surrounded by a second flexible component shrunk on to the first in a manner which preserves the flexibility of each, substantially as described.

4. The method of forming a duplex spring 45 which consists in forming wire windings about a temporary core, in removing the core, in expanding the windings under the action of heat, and finally in inserting a permanent core larger than the first within 50 the windings while still expanded, substantially as described.

5. The method of forming a duplex spring which consists in forming windings of 55 spring material about a temporary core, in removing the core, in expanding the windings under the action of heat, and finally in shrinking the windings upon a permanent 60 spring core to establish an inseparable engagement therewith, substantially as described.

6. The method of forming a duplex spring which consists in winding a length of spring 65 material about a form which is of uniform cross sectional size from end to end, in removing the form from within the surrounding windings, in expanding the windings whereby the space interiorly thereof is enlarged, in fitting within the space interiorly of the windings a longitudinally extending spring, and finally in contracting the outer windings tightly upon the inner spring 70 to connect the one permanently to the other, substantially as described.

CHARLES H. LEINERT.
